PNEUMATIC TURBINE DRIVE CONTROL SYSTEM

Edward C. Palmenberg, Nanuet, N.Y., assignor to Bendix Aviation Corporation, Teterboro, N.J., a corporation of Delaware

Application January 20, 1955, Serial No. 483,083

12 Claims. (Cl. 137—27)

This invention is concerned with providing new and useful improvements in controlling the operation of pneumatic turbine drives. It particularly concerns a novel and practical pneumatic turbine drive control system having a number of novel features and desirable advantages. The invention provides a system whereby the speed of a pneumatically driven turbine is held under control; it serves to hold the speed of the turbine to a desirable rate when loaded or unloaded, and provides protective measures against overspeeding.

A feature of the invention is present in certain structures whereby a double check against overspeeding of the turbine engine is provided, one of which serves as an emergency control in the event the other fails to function.

Another feature of the invention lies in various valve structures and arrangements whereby the flow of pressure air that drives the turbine is controlled.

The invention further lies in the structure, simple organization and arrangement of the various elements of the control system, and in their cooperative association with one another, whereby an efficient and practical turbine drive control system is obtained.

A general object of the invention is, therefore, to provide an improved, practical, and efficiently operating turbine drive control system.

A more particular object of the invention is to provide an uncomplicated system for controlling the speed of a pneumatic turbine drive.

Another object, though not the last, is to provide simple and efficiently operating valve structures in cooperative association with one another to control the speed of a turbine drive.

The foregoing objects and advantages of the invention will appear more fully hereinafter from a consideration of the detailed description which follows, taken together with the accompanying drawings wherein an embodiment of the invention is illustrated. It is to be expressly understood, however, that the drawings are for purposes of illustration and description, and are not to be construed as defining the limits of the invention.

In the drawings:

Fig. 1 is a schematic view showing the relative association of the various units of the system with one another;

Fig. 2 is a longitudinal cross section through the turbine drive unit;

Fig. 3 is a similar section through the pressure air flow control unit;

Fig. 4 is a right end fragmentary view of Fig. 3;

Fig. 5 is a left end view of Fig. 3, wherein the ball valve is sectioned; and

Fig. 6 is a cross section through the hydraulic pressure relief valve.

In general, the control system of the present invention includes a turbine drive unit adapted to be pneumatically driven by pressure air supplied to it from a suitable

2

source through a pressure air flow control unit. The latter includes pressure air outflow valve control mechanism whereby a proper flow of pressure air from the flow control unit to the turbine is provided. When the speed of the turbine increases beyond a predetermined rate, such as may happen when unloading, certain speed sensing means operable by the turbine drive cooperates with hydraulic pump means, also operated by the turbine drive, to cause the outflow valve control mechanism to decrease the pressure air supply to the turbine and thereby curb the speed of the latter.

The pressure air flow control unit also includes pressure air inflow valve control mechanism, whereby inflow air to the flow control unit is held at a constant pressure. Associated with this air inflow valve control mechanism are certain controls automatically operable by the turbine drive upon the latter attaining an excessive speed, as may happen when the outflow pressure air controls are malfunctioning. These associated controls, when operated, serve to cut off the inflow supply of pressure air to the flow control unit entirely, or to the extent required to restore the speed of the turbine to normal.

In detailing the operation of the system of the present invention and the structures of the cooperating parts thereof, reference is now directed to the several drawings. The turbine drive unit 1 of the present invention (Figs. 1, 2, 3) includes a turbine member 2 of an associated jet aircraft, though it is understood the invention may well be employed in other work situations. The turbine member is carried by a drive shaft 3 that is supported for rotatable movement in bearings 4 carried in a proper housing 5. The turbine member is pneumatically driven by pressure air fed to it through the pressure air flow control unit 6. The pressure air flows from unit 6 through a connected scroll 7 and ducts 8 to attack the turbine blades, the used air passing out through an exhaust duct 9.

The pressure air flow control unit 6 (Fig. 3) includes an elongated sleeve or cylinder member 10 having a plurality of inflow ports 11 through the wall thereof, just to the right of center. An inlet scroll 14 mounted about the left portion of cylinder 10 communicates through ports 11 with the interior of the cylinder; outlet ports 12 communicate the interior of the cylinder with an outlet scroll 15 mounted about the right portion of cylinder 10. Inlet scroll 14 provides an inlet end 16 adapted for connection to a proper source of pressure air supply, not shown. Valve mechanism 18 incorporated in the left end of the cylinder regulates the inflow of pressure air through ports 11 to the interior of the cylinder. Outlet scroll 15 provides an exit end 19 connected, as by a clamp 21, to the inlet end of the turbine scroll 7. Valve mechanism 22 incorporated in the right end of cylinder 10 regulates the outflow of pressure air from the interior of the cylinder through ports 12 to the turbine.

Relative to the structure of the outflow pressure air control valve mechanism 22, the right end of cylinder 10 is closed over by a crown member having an annular flange 23 which overlaps an end wall of cylinder 10 and is secured to the wall of the outlet scroll 15. A crown portion 24 of the crown member projects axially into cylinder 10 in spaced relation to the wall of the latter. In the innermost end of the crown is securely fitted a plug member 25 carrying an annular flanged free end 26. Surrounding the crown element and limited between flange 26 and a dished ring 27 is a compression coil spring 28. The dished ring is slidable along the crown piece 24. In slidable contact with the cylinder wall is a short sleeve member 29, the right end of which limits against the inner face of crown flange 23, and the left end 31 of which terminates at the right edges of the several out-

flow ports 12. The dished ring 27 is fitted in the right end of sleeve 29 and locked to the sleeve by a snap ring 32. Fitted in the left end of the sleeve is a radially perforated cap or dished member 33 that is locked to the sleeve by a snap ring 34. Sleeve member 29 serves as a valve to cover and uncover the outflow ports 12. The arrangement is such that, the coil spring 28 normally tensions sleeve 29 to the right, wherein such position the outflow ports 12 are uncovered by sleeve 29. Moving the cap member 33 to the left will carry sleeve 29 and dished ring 27 along with it against the tension of coil spring 28; this action will draw sleeve 29 over the outflow ports and, according to the extent of such movement, will diminish the outflow of pressure air to the turbine. Coil spring 28 acts to restore the sleeve, as leftward pressure against the cap member 33 is cut off. It is plain that the speed of the turbine will be proportionately curbed with the decrease in pressure air flow. The sleeve member 29 is operated by hydraulic means, and is governed in its movement by suitable turbine speed sensing means.

The hydraulic means for operating sleeve valve 29 includes a piston cylinder 35, capped at one end by plug member 25. In cylinder 35 reciprocates a piston 36 having a rod 37. The latter is slidable through an axial hole of plug 25, and normally limits against a central wall area 38 of cap member 33. The right end of piston cylinder 35 communicates with a fitting 39. The piston is driven by pressure oil pumped by a gear pump 41 (Fig. 2) from a sump section of the housing to fitting 39. Suitable gearing 42 operatively connects the gear pump to the turbine drive shaft 3. Communication of the outlet of the gear pump to piston cylinder 35 is normally blocked by a speed sensing valve 43. Interposed in an oil line 44, between the outlet of the gear pump and an inlet port 55 of the speed sensing valve, is a pressure relief valve 46 (Figs. 1, 6). The latter relieves to sump over passage 40 excessive pump oil pressure developing in line 44.

The speed sensor valve 43 normally blocks pressure oil flow from operating the piston 36 of the pressure inflow control unit 6 during normal speeds of the turbine. But when the turbine exceeds this normal speed, the speed sensor valve is caused to progressively open. In its structure, the speed sensor valve (Fig. 2) includes a cup member 47 having an axially extending hollow shaft portion 48 which is geared at 49 to the turbine drive shaft and rotates in a suitable bearing 50. Slidable in the shaft is a valve rod 51 having a headed end 52 that is slidable in cup member 47. A coil spring 53, limited between a cup 54 and the valve head 52, tensions rod 51 to the right where the shank of the latter closes over or blocks off port 55 that communicates the hollow shaft 48 with the gear pump line 44. Suitable adjusting means 56 is provided to adjust the tension of spring 53, as desired. A plurality of equally spaced bellcrank elements 57 are pivoted in individual slots 58 radially about cup 47. Each bellcrank includes a short arm having a roller end 59 that underlies valve head 52, and also includes a weighted fly-arm 61. The operation of the sensor valve 43 and its relation to the gear oil pump 41 is such that, as the turbine speed increases beyond a predesigned maximum, the weighted bellcrank arms 61 fly outward and cause valve rod 51 to be drawn leftward. This action progressively draws a tapered reduced section 62 of rod 51 over port 55. This opens communication of the gear pump line 44 through port 55, the interior of hollow shaft 48, and a port 63 to the fitting 39 of unit 6 (Fig. 3) and to the associated piston 36. A thickened end 64 of the valve rod 51 blocks escape of oil through the open right end of sensor shaft 48. Pressure oil communicated to piston 36 actuates the latter to move its rod 37 against the cap member 33, causing the latter to progressively draw the sleeve element 29

over the outflow ports 12. With this action, the flow of pressure air to drive the turbine is decreased, causing the turbine to decelerate to normal speed. Coil spring 28 acts to progressively restore cap 33 and piston 36 as the flow of pressure oil is again blocked consequent upon restoration of the valve rod 51. The pressure oil carried to piston 36 is drained to sump as the piston restores through a narrow bleeder line 60 in an adjustable screw 60A, passage 65 and a sump connecting fitting 66 shown schematically in Fig. 1 and indicated by dotted lines in Fig. 3. It is clear that, as the sensor valve rod 51 is progressively drawn leftward with increasing turbine speed the decline of the tapered surface 62 thereof increases to progressively provide a greater oil flow through port 63 to the piston 36 and, as a consequence, causes a further closing of the outflow ports 12. It is also clear that, as the turbine speeds above a predetermined rate and decelerates back again with unloading and loading of the turbine, the valve sleeve 29 will oscillate back and forth over the outlet ports 12 to provide a controlled pressure air flow to the turbine. It is to be noted that the left portions of the outlet port 12 are tapered or cut off at an angle. This serves to prevent an abrupt closing off of the air flow therethrough.

Plug 25 through which the hydraulic piston rod 37 moves is subject to considerable heat that develops in the interior of cylinder 35. The piston cylinder also develops heat in the operation of the piston. The piston cylinder and the plug are kept cool by circulating the gear pump fluid over these parts on its return to sump. To this end, a shell 67 surrounds the piston cylinder and provides a space 68 between the two. This shell is secured at one end about plug 25 and is closed over at the other end by a block 69. In this block is mounted the fitting 39 which communicates by a passage 70 with the piston. Branching off from this passage through a bleeder line 60 is the narrowed sump return line 65. The latter communicates through block 69 with the space 68 and also with the sump return fitting 66 indicated in Fig. 3 by dotted lines. Space 68 communicates with the piston cylinder 35 through a plurality of ports 71. By this arrangement, hydraulic fluid bleeding through the passage 65 circulates in the space 68 about cylinder 35 and through the ports 71 to cool both the cylinder and plug 25, and returns to sump by way of the fitting 66.

The pressure air inlet control valve mechanism 18 incorporated in the left end of cylinder 10 serves to maintain a constant inlet pressure air flow through ports 11, though the air pressure through the inlet scroll 14 may vary. This valve mechanism operates to oscillate over the ports 11, decreasing or increasing the flow of the cylinder 10 accordingly as the pressure through the scroll 14 varies, whereby a constant pressure flow through ports 11 is provided.

The structure of the valve mechanism 18 includes a crown member 72, a flange 73 of which overlaps the left end wall of cylinder 10 and is secured to the end wall of the intake scroll. The crown member 72 projects axially into cylinder 10 in spaced relation to the wall of the latter. A coil spring 74 surrounds the crown and is tensioned between a stationary flange 75 at one end and a dished ring 76 at the other. Ring 76 is fitted in one end of a valve sleeve 77 that is slidable in the cylinder 10 in contact with the wall of the latter. Ring 76 is locked to the sleeve by a snap ring 78. A perforated cap 79 is fitted in the opposite end of the sleeve and is locked therein by a snap ring 80. The sleeve is tensioned leftward by spring 74 to a position where its right edge is removed from the pressure air inlet ports 11. The coil spring retaining flange 75 is part of a plug 81 that is fitted fast in one end of a piston cylinder 82. The latter is fitted fast in the inner end of crown member 72. The opposite end of piston cylinder 82 is fitted with a plug 83, to which axially connects a fitting 84. Slidable in cylinder 82 is a piston 85. Axially extending from the head

of piston 85 is an extension 86 that opens through its free end. A coil spring 87, retained at one end in the well formed by a skirt wall 88 surrounding extension 86, and limited at the other end against the plug element 81, tensions the piston head 85 leftward against the inner face of plug 83. Slidable in the cylinder formed by extension 86 is a further piston 89 having a cup head 90 that opens through an axially extending hollow shaft portion 91 thereof. Shaft 91 is slidable through a boss 92 of plug 81 and limits against a central solid area 93 of cap member 79. Inlet ports 11 communicate through perforations 94 of cap member 79 to space 95, and through cross holes 96 in the projecting end of shaft 91 to the cup head 90 of piston 89. The structure is such that, inflow air passing through inlet scroll 14 enters the interior of cylinder 10 through ports 11 and passes from the interior of cylinder 10 through ports 12 to attack the turbine. This inlet air also passes through the perforated cap 79 and the cross holes of hollow shaft 91 to the piston cup 90. Up to a predesigned force of coil spring 74, the pressure air has no effect on piston 89. However, when the intake air pressure exceeds the opposed tension of spring 74, the air acts upon piston 89, which in turn forces the cap 79 to carry sleeve 77 over the intake ports 11. Sleeve 77 progressively closes over the ports until the diminished inflow pressure is balanced by the opposed pressure of compressed spring 74. By this arrangement, it can be seen that variations in the intake pressure air flow above a predesigned degree will cause sleeve 77 to oscillate back and forth over ports 11 to provide a constant pressure air flow to the interior of the cylinder 10, and then to the turbine. It is to be noted, that the right ends of the inlet ports 11 are tapered to avoid any abrupt shutting off of air flow.

Other means is provided to control the turbine against overspeeding in cases of emergency arising due to malfunctioning of the outflow valve control mechanism 22, or from other causes. This overspeed mechanism (Figs. 1, 3, 2, 5) includes a dump valve 97, operable by a speed governor sensor device 98. Its purpose is to cause pressure air from the inlet scroll 14 to be diverted to the piston 85. This will as a consequence, effect a rightward movement of sleeve 77 through piston 85 acting on piston 89 so as to close the ports 11 and shut off the pressure air flow to the turbine.

In this overspeed protective means the fitting 84 communicates the piston cylinder 82 by a line 99 to one end 100 of an elongated chamber of a ball valve 101. The opposite end of the chamber communicates through a fitting 102 and line 103 with the dump valve 97.

In the ball valve (Fig. 5) a slidable piston block 104 biased by a spring 105 seats a ball 106 in the valve over the inlet end and also over a nearby passage 107. The latter extends off laterally from the ball valve chamber and communicates with the intake scroll 14.

Dump valve 97 (Fig. 2) includes a piston 108 slidable in a chamber of the valve. This piston has a conical head which seats in an outlet opening of the valve and is biased to seating position by a spring 110. The piston carries an operating pin 111 that projects through the seat opening. The dump valve piston is pressurized to closed position over its outlet by pressure air which leaks through the passage line 103 from port 107 around the ball valve 106 and block 104. This pressure builds up in the line 103 against the block and ball, and serves to seal off communication of passage 107 with piston line 99.

The arrangement is such that, should the operating pin 111 of the dump valve be pressed inward, the pressure in line 103 will be released, and as a consequence, pressure air through passage 107 will move the ball 106 free of line 99 and will flow over line 99 to attack the large area of piston 85. The latter action, as previously explained, will effect movement of sleeve 77 and a consequent shutting off of pressure air through ports 11 to cause deceleration of the turbine.

The operating pin 111 of the dump valve is automatically operable by the speed sensing device 98 (Fig. 2). The latter comprises a cup member 114 having an axially extending hollow shaft 115 that is carried fast in the hub end of turbine shaft 3. Slidable in the cup is a mushroom head 116 of a piston rod 117. The latter is adapted to slide in the hollow shaft 115. A coil spring 118, retained in the cup by a snap ring 119 at one end, tensions the mushroom piston head toward the base of cup member 114 to cover a plurality of fly balls 120. The dump valve is supported axially in a wall of the turbine exhaust duct 9, and the operating pin 111 of the dump valve normally abuts against the exposed mushroom piston head 116. The operation is such that, upon the turbine overspeeding sufficiently to cause the fly balls 120 to centrifugally force the mushroom head outward from its cup, the pin 111 will be depressed to operate the dump valve and effect the actions previously mentioned.

Although an embodiment of the invention has been illustrated and described in detail, it is to be expressly understood that the invention is not limited thereto. Various changes can be made in the design and arrangement of the parts without departing from the spirit and scope of the invention as the same will now be understood by those skilled in the art.

What is claimed is:

1. A turbine speed control system including a turbine drive, a valve for conveying fluid under pressure from a source to the turbine drive, the valve including fluid flow pressure control means operable by the incoming fluid under pressure to maintain a constant pressure of the fluid flow through the valve, speed sensing actuator means operable by the turbine drive above a rated speed of the latter, shut off fluid flow control means included in the valve operatively associated with the speed sensing actuator means to shut off the flow of fluid under pressure through the valve, said shut off flow control means including piston means operable to shut off pressure fluid flow through the valve, spring means normally tensioning the piston means to ineffective position, a conduit connecting the piston means with a source of pressure fluid effective to operate the piston means against the tension of the spring means to effective shutoff position, blocking valve means normally blocking flow of pressure fluid through the conduit to the piston means, and means operable by the speed sensing actuator to relieve the blocking effect of the blocking valve means so as to cause a flow of pressure fluid through the conduit to operate the piston means.
2. A turbine speed control system including a turbine drive, a valve for conveying fluid under pressure from a source to the turbine drive, the valve including fluid flow pressure control means operable by the incoming fluid under pressure to maintain a constant pressure of the fluid flow through the valve, speed sensing actuator means operable by the turbine drive above a rated speed of the latter, shut off fluid flow control means included in the valve operatively associated with the speed sensing actuator means to shut off the flow of fluid under pressure through the valve, said pressure flow control means including a valve cylinder reciprocal over inlet ports of the valve to vary the pressure fluid flow therethrough, calibrated spring means normally biasing the valve cylinder free of the inlet ports, and piston means operable by pressure fluid flowing through the inlet ports to move the valve cylinder progressively over the ports until the inflow pressure against the piston balances the opposing tension of the calibrated spring means.
3. In a pressure air driven turbine speed control system, a turbine, a drive shaft carrying the turbine, a first turbine speed sensing means centrifugally operable by the drive shaft upon the latter exceeding a rated speed, other turbine speed sensing means centrifugally operable by the drive shaft upon the latter exceeding a further

rated speed, a relay valve unit for conveying a flow of pressure air from a connected source to the turbine to drive the latter and the associated drive shaft, the relay unit including an inlet valve, and an outlet valve and having an inlet-outlet chamber common to both valves, the outlet valve being responsive to the first turbine speed sensing means to control the flow of pressure from the common chamber to the turbine, and the inlet valve being responsive to the other turbine speed sensing means to shut off the flow of pressure air to the common chamber.

4. In a turbine speed control system as in claim 3, wherein the inlet valve includes means operable by the flow of pressure air from the source to the common chamber to control the extent of flow of pressure air to the common chamber.

5. An air driven turbine speed control system comprising in cooperative combination, a turbine operable by pressure air flow, a drive shaft carrying the turbine, a relay valve unit for conveying a flow of pressure air from a connected source to the turbine, the relay unit including an inlet valve and an outlet valve and having an inlet-outlet chamber common to both valves, the outlet valve being hydraulically operable to vary the flow of pressure air from the common chamber to the turbine upon the turbine exceeding a first rated speed, a gear pump continuously operable by the turbine drive shaft to pump hydraulic fluid from a sump to operate the outlet valve, a speed sensing valve normally blocking hydraulic fluid flow to the outlet valve, a check valve operable by the blocked hydraulic fluid flow to pass the latter to sump, and the speed sensing valve being centrifugally operable to allow flow of the hydraulic fluid to the outlet valve upon the turbine exceeding the rated speed.

6. An air driven turbine speed control system comprising in cooperative combination, a turbine operable by pressure air flow, a drive shaft carrying the turbine, a relay valve unit for conveying a flow of pressure air from a connected source to the turbine, the relay unit including an inlet valve and an outlet valve and having an inlet-outlet chamber common to both valves, the outlet valve being hydraulically operable to vary the flow of pressure air from the common chamber to the turbine upon the turbine exceeding a first rated speed, a gear pump continuously operable by the turbine drive shaft to pump hydraulic fluid from a sump to operate the outlet valve, a speed sensing valve normally blocking hydraulic fluid flow to the outlet valve, a check valve operable by the blocked hydraulic fluid flow to pass the latter to sump, and the speed sensing valve being centrifugally operable to allow flow of the hydraulic fluid to the outlet valve upon the turbine exceeding the rated speed, the inlet valve including spring restrained means operable by inlet pressure air flow to the common chamber to vary the inlet flow to the chamber until the pressure of the inflow air to the spring restrained means balances the force of the restraining spring.

7. An air driven turbine speed control system comprising in cooperative combination, a turbine operable by pressure air flow, a drive shaft carrying the turbine, a relay valve unit for conveying a flow of pressure air from a connected source to the turbine, the relay unit including an inlet valve and an outlet valve and having an inlet-outlet chamber common to both valves, the outlet valve being hydraulically operable to vary the flow of pressure air from the common chamber to the turbine upon the turbine exceeding a first rated speed, a gear pump continuously operable by the turbine drive shaft to pump hydraulic fluid from a sump to operate the outlet valve, a speed sensing valve normally blocking hydraulic fluid flow to the outlet valve, a check valve operable by the blocked hydraulic fluid flow to pass the latter to sump, and the speed sensing valve being centrifugally operable to allow flow of the hydraulic fluid to the outlet valve upon the turbine exceeding the rated speed, the inlet valve including spring restrained means operable by inlet pres-

sure air flow to the common chamber to vary the inlet flow to the chamber until the pressure of the inflow air to the spring restrained means balances the force of the restraining spring, spring restrained piston means operable by pressure air from the source to cause the spring restrained means to shut off the inlet flow to the chamber, a conduit branch from the source conveying pressure air to the piston means, a dump valve normally blocking communication of the conduit branch with the piston means, and actuator means centrifugally operable by the turbine drive shaft to operate the dump valve to unblock communication of the conduit branch with the piston means when the turbine drive shaft exceeds a further rated speed.

8. A pressure air flow control unit for communicating pressure air from a source to drive a prime mover, comprising an elongated cylinder having a plurality of inflow ports located off to one side of the center of the cylinder and a plurality of outflow ports located off to the other side of center, a pressure air inflow scroll mounted about a first end portion of the cylinder and providing communication from a connected pressure air source to the interior of the cylinder through the inflow ports, a pressure air outflow scroll mounted about an opposite second end portion of the cylinder and providing communication of pressure air flow from the interior of the cylinder through the outflow ports to an associated prime mover, first valve means in the first end portion of the cylinder operable to control the degree of pressure air flow through the inflow ports to the interior of the cylinder, the first valve means comprising a valve sleeve slidable over the inflow ports to diminish the air flow therethrough, spring means normally biasing the valve sleeve free of the inflow ports, piston means associated for sliding the sleeve and operable by pressure air flow from within the interior of the cylinder to slide the sleeve against the bias of the spring means progressively over the inflow ports as the pressure flow of the inflow air increases beyond a rated maximum, and second valve means operable in the second end portion of the cylinder to control the extent of pressure air outflow from the interior of the cylinder through the outflow ports, the second valve means comprising a valve sleeve slidable over the outflow ports to diminish the size thereof, spring means normally biasing the valve sleeve free of the outflow ports and hydraulic piston means operable by the output of hydraulic pump means to progressively move the valve sleeve over the outflow ports against the bias of the last mentioned spring means.

9. The combination of a pressure air flow control unit as in claim 8 with centrifugally operable valve means interposed intermediately of the output of the hydraulic pump and the hydraulic piston and normally blocking communication of the one with the other, and means for operatively associating the centrifugally operable valve means with the prime mover.

10. A turbine speed control system comprising valve means including a first valve member, fluid pressure responsive means to operate said first valve member so as to regulate a variable pressure fluid to a constant pressure to drive the turbine, a second valve member, speed responsive control means operable by the turbine to adjust said second valve member so as to regulate the flow of pressure fluid through the valve means inversely to the speed of the turbine after the latter exceeds a rated maximum speed, and other speed responsive control means operable by the turbine to adjust said first valve member so as to shut off the flow of pressure fluid through the valve means to the turbine after the turbine exceeds a further rated maximum speed.

11. A constant speed power apparatus comprised of a fluid-operated turbine, fluid supply means including a pressure-regulating inlet valve and an adjustable flow valve in series operatively connected to said turbine for delivering a constant-pressure variable supply of working fluid to said turbine, governor means responsive to the speed

of said turbine connected to said flow valve by hydraulic means which is pressurized by said turbine to regulate the fluid flow to said turbine and hence the speed thereof, speed responsive means actuated by said turbine operatively connected to close said pressure-regulating valve when said governed flow valve fails to operate, and said pressure regulating valve and said speed responsive means being constructed so that inlet fluid closes said pressure regulating valve when the flow valve fails to operate.

12. A speed control system comprising a turbine drive, relay conduit means for communicating pressure fluid from a source to the turbine drive, a first valve member to control an inlet to said conduit means, pressure responsive means connected downstream of said inlet to operate said first valve member so as to reduce the fluid pressure in said conduit means to a predetermined constant pressure upon the fluid varying in pressure above a predetermined maximum, a second valve member to control an outlet from said conduit means, speed responsive means operable by the turbine upon the latter exceeding a pre-

determined speed to adjustably position said second valve member so as to vary the flow of pressure fluid from the relay conduit means to the turbine inversely as the turbine speed increases, other means, operable centrifugally by the turbine upon the latter overspeeding beyond a further predetermined maximum speed, arranged to close the first valve member so as to shut off the flow of fluid from the source to the relay conduit means.
